Assignor to

The Lowell Manufacturing Company,
Letters Patent No. 1636, dated Aug. 12, 1862,

The schedule referred to in these Letters Patent and making part of the same.

To all whom it may concern:

Be it known that I, Elmer J. Ney, of Lowell, in the County of Middlesex and State of Massachusetts, have originated and designed a new Pattern for Carpets or other fabrics, of which the following is a full, clear and exact description, reference being had to the accompanying drawings making part of this specification.

This specification refers to that part of the drawings lying between the blue lines. A. is a large oblong figure, composed of the small figure 1. ground of blocks 2. waving band 3. lace work 4. scrolls 5. and outside frame 6. 7. is a set figure surrounded by the wreath 7.

E and E', at the sides when matched, form a figure composed of diamonds, and surrounded by the scrolls 8. 8. and 9. 9. Figures a. and b. b. are vines running from the frame 6. and enclosing the scrolls 8. 8. and 9. 9.

The four corners when matched form figures similar in form and surroundings to E. and E', at the sides.

The colors employed for the different portions of the design may be varied to suit the taste and wish of the manufacturer.

Claim.

What I claim as my invention and desire to secure by Letters Patent, is the design or pattern, for Carpets or other fabrics, herein set forth, witness,

William Murkland,

Robert R. Campbell.
